UNITED STATES PATENT OFFICE.

THOMAS ALDEN CRABTREE, OF EAST SURRY, ASSIGNOR OF ONE-HALF TO
BENJAMIN MORRILL, OF BLUE HILL, MAINE.

UMBRELLA.

SPECIFICATION forming part of Letters Patent No. 355,142, dated December 28, 1886.

Application filed June 28, 1886. Serial No. 206,417. (No model.)

To all whom it may concern:

Be it known that I, THOMAS ALDEN CRABTREE, a citizen of the United States, and a resident of East Surry, in the county of Hancock and State of Maine, have invented certain new and useful Improvements in Umbrellas; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of as much of an umbrella as will show my improvement. Fig. 2 is a similar view on an enlarged scale, showing the improvement in position when the umbrella is folded; and Fig. 3 is a perspective view of the parts of the improvement detached.

Similar letters of reference indicate corresponding parts in all the figures.

My invention has relation to slides for umbrellas; and it consists in the improved construction and combination of parts of such a slide, having a bayonet-slot at the upper and lower end for engaging studs at the upper and lower portions of the umbrella-staff, as hereinafter more fully described and claimed.

In the accompanying drawings, the letter A indicates the staff of the umbrella, which staff may be of any suitable material, and may have any suitable ornamentation, and which is formed with two studs, B and C, respectively at the upper and lower portions of the staff, the portion nearest the handle being in this case referred to as the lower end. Sliding upon the staff between the studs B and C is a runner, D, the ends of which are provided with the outwardly-flaring notches E, each notch having a laterally-extending recess, F, at its base. An outer sleeve, H, is secured upon the runner by means of a pin, L, near the lower end of the runner, which projects through the slot K near the lower end of the outer sleeve, said slot being shorter than the mouth or outer portion of the notches E.

An ordinary notch, M, is secured to the upper end of the sleeve H. At the lower end of the runner is a milled ring, G, for the purpose of

securing a firm hold of the runner when it is desired to turn the same on the shaft. As the notch is held from turning around the runner by the ribs and braces, which are secured to the crown-notch by the usual manner, it will be seen that the runner D can be readily turned around the staff within the limits of the slot K, the sleeve H affording as long a brace or stay for the notch M as is found in the runners used upon the ordinary umbrellas.

When it is desired to raise the umbrella, the runner D is turned around the staff until the recess F is disengaged from the lower pin, C, when it can be pushed up the staff until the upper pin, B, enters the upper notch, E, when a slight turn of the runner causes the upper recess, F, to engage with the pin B, which prevents the runner from sliding down the staff. To close the umbrella, the above process is reversed.

Previous to my invention umbrella-runners have been made with a shallow groove or channel around them, in which a sleeve having the notch-piece around it has been secured; but this method is objectionable, as the only support for the entire weight of the top is the lower side of the shallow groove, which would soon wear sufficiently to permit the sleeve to slip down over the runner. Another objection to it is the difficulty of fitting the sleeve in such a groove; hence I do not wish to claim such a construction; but

What I have invented, and desire to secure by Letters Patent, is—

The combination, with a runner for umbrellas, having a recess at the base of an outwardly-flaring notch at each end, of a pin projecting from its intermediate portion and a milled ring around its lower portion, and an outer sleeve around said runner having a notch around its upper portion and a slot near its lower portion.

In testimony that I claim the foregoing as my own I have hereunto affixed my signature in presence of two witnesses.

THOMAS ALDEN CRABTREE.
